Patented Apr. 27, 1926.

UNITED STATES PATENT OFFICE.

WILLIAM H. ADAMS, OF NEW YORK, N. Y.

PRECAST PLASTER-WALL SECTION AND MEANS FOR PACKING SAME.

Original application filed July 4, 1925, Serial No. 34,995. Divided and this application filed September 23, 1925. Serial No. 58,205.

To all whom it may concern:

Be it known that I, WILLIAM H. ADAMS, a citizen of the United States, residing at New York city, N. Y., have invented certain new and useful Improvements in Precast Plaster-Wall Sections and Means for Packing Same, of which the following is a specification.

This invention relates to improvements in pre-cast plaster wall sections and more specifically to means for packing said sections for transportation.

In my application Serial No. 34,995 filed June 4, 1925, I have disclosed a novel pre-cast plaster wall section and means for packing the same, and the present application is a division of application Serial No. 34,995.

It is customary in manufacturing wall boards or the like with a body of gypsum or similar material to enclose the opposite edges of the board and the covering is permanently secured to said edges. I have found that the edges of the board need not be covered when they are placed on the wall, but these edges may be left raw or uncovered, to facilitate the placing of plaster or the like at the joints, when the boards or sections are placed on the wall. To permit this, however, the opposite edges of each section must be made with rabbets at both sides thereof. If rabbets are formed at both sides of the opposite edges of each board, it is obvious that the edge portions of each board will be of less thickness than the central portion of the board and consequently when a number of such boards are superposed for shipment, the edge portions of the boards will not contact with each other but spaces will be left between the same. As a result the edge portions are liable to vibrate and cause cracking of the sections and loosening of the raw material at the edges of the sections. To overcome this disadvantage I have discovered that the vibration may be prevented and the raw edges protected, if substantially U-shaped strips of paper are placed over the rabbet edge portions of the pre-cast plaster wall sections when the same are to be shipped.

It is therefore the primary object of the present invention to provide pre-cast plaster wall sections of special formation, with loose edge strips, which not alone prevent vibration of the strips when they are placed

in superposed relation, but protect the raw edges of such sections.

With the foregoing object outlined and with other objects in view which will appear as the description proceeds, the invention consists in the novel features hereinafter described in detail, illustrated in the accompanying drawing and more particularly pointed out in the appended claim.

Referring to the drawing:

Figure 1 is a perspective view of a number of pre-cast plaster wall sections constructed in accordance with my invention, and in superposed relation for the purpose of shipment; the opposite rabbeted edge portions of each section being provided with U-shaped protecting strips of paper or the like.

Fig. 2 is an end view of four of these sections in superposed relation and partly in section to facilitate illustration.

At the outset of the detail description, it may be stated that the improved pre-cast plaster wall sections in accordance with this invention may be manufactured by machines similar to those employed in making plaster boards. During manufacture a facing strip 1 of paper or the like is fed along the table of the machine and the table will be provided with raised portions to form the rabbets 2 at the edge portions of the paper. As the paper moves along, a layer 3 of gypsum or any other similar material of the character used with plaster boards, is deposited on the paper sheet 1. Afterwards the surface of the layer 3 may be troweled off to provide rabbets 4 at the upper side of the section, and finally a surface sheet 5 of paper or the like may be placed over the layer 3, and its edge portions 6 be bent into the rabbets 4. In this way I obtain a plaster wall section provided with rabbeted edge portions and having raw edges 10 all around. These raw edges enable me to paint the edges of the sections with plaster or the like before they are butted together, or to fill the joints with plaster after they are nailed to the wall, in order to produce a wall or ceiling of solid plaster or other cementitious material, thus deriving the benefit of better fire protection and insulation, also more substantial construction, as the walls and ceiling thus formed will be solid as concerns the basic material.

The sections formed in accordance with

the foregoing description, are exactly the same as those disclosed in the parent application Serial No. 34,995 with the exception that in the parent application, I have shown 5 each section as provided with an internal fluted reinforcing strip. The sections in accordance with the divisional application may of course have such reinforcing strips if desired.

10 While the rabbets at the opposite edge of the sheet, facilitate the formation of the joints they are open to a disadvantage in shipment. If a number of the sections are placed in superposed relation for transportation, vibration may cause the reduced edge 15 portions to eventually crack, and to prevent this I place a U-shaped bending strip 11 loosely over the rabbeted side edge portion of each section. These binding strips will 20 protect the raw side edges and will enter the rabbets 2 and 4, and the outer surfaces of its flaps 12 will be flush with the outer surfaces of the facing sheets 1 and 5. This is clearly shown in Fig. 2, and it will be 25 appreciated by those skilled in the art that such binding strips will prevent vibration

from fracturing the edges of the sections when said sections are in superposed relation during shipment.

From the foregoing it is believed that the 30 invention may be readily understood by those versed in the art, and it is obvious that changes may be made in the details disclosed without departing from the spirit of the invention as expressed in the claim. 35

What I claim and desire to secure by Letters Patent is:

A package including a series of superposed pre-cast plaster wall sections, each provided with rabbets on each side of opposite edge portions of the same, of substantially U-shaped binding strips loosely arranged at the rabbeted edges of the sections and extending into the rabbets, the outer surface of the arms of each binding 40 strip being in the same plane as the outer surfaces of the body of the wall section which it engages for preventing the rabbeted edge portions from vibrating and cracking 45 during shipment.

In testimony whereof I affix my signature. 50
WILLIAM H. ADAMS.
